UNITED STATES PATENT OFFICE.

LUTHER L. FRIERSON, OF MOUNT PLEASANT, AND JACOB BARKER, OF COLUMBIA, TENNESSEE.

PACKING AND REFRIGERATING VESSEL.

SPECIFICATION forming part of Letters Patent No. 431,941, dated July 8, 1890.

Application filed January 30, 1890. Serial No. 338,633. (No model.)

To all whom it may concern:

Be it known that we, LUTHER L. FRIERSON and JACOB BARKER, citizens of the United States, residing, respectively, at Mount Pleasant and Columbia, in the county of Maury and State of Tennessee, have invented new and useful Improvements in Packing and Refrigerating Vessels, of which the following is a specification.

10 This invention relates to that type of packing and refrigerating structures for preserving and transporting poultry, milk, and other food products wherein a closed containing-vessel is arranged in an envelope or external 15 casing, with an antiseptic packing between the two, as in Letters Patent No. 410,481, issued September 3, 1889.

The objects of our invention are to improve the prior constructions, and to provide novel, 20 simple, and efficient means for retaining the containing-vessel in a fixed position relatively to the envelope, and at the same time form part of the bottom wall of the ice-chamber.

The objects of our invention we accomplish 25 by the features of construction and the combination or arrangement of devices hereinafter described in detail and specifically set forth in the claims, reference being made to the accompanying drawings, in which—

30 Figure 1 is a vertical central sectional view of a packing-refrigerator embodying our invention; Fig. 2, a similar view of the upper end portion of the structure, showing a modification; and Fig. 3, a broken sectional view 35 showing a variation of the parts exhibited in Fig. 2.

In order to enable those skilled in the art to make and use our invention, we will now describe the same in detail, referring to the 40 drawings, wherein—

The numeral 1 indicates an external casing that we term an "envelope," and which may be polygonal or any other desired shape in cross-section, but is preferably circular and 45 of the same general configuration as an ordinary barrel. This envelope is coated by painting or otherwise internally and externally with a proper water-proof material for preserving the wood and preventing it from becoming saturated with water. The contain-

ing-vessel 2 is preferably of metal, and is provided with an inclined breast 3, from which rises a neck 4, that receives the tightly-fitting cover 5, and the envelope is furnished with a tight cover 6, detachably held in position by 55 fastenings 7—such, for example, as described and shown in the Letters Patent before mentioned. The space between the external sides and the bottom of the containing-vessel and the interior of the envelope is filled with an 60 antiseptic packing of charcoal or other material suitable for the conditions required, which packing terminates at or near the point where the breast 3 joins the side of the containing-vessel. An annular ring or band 8 65 is rigidly secured to the inner side of the envelope directly above the antiseptic packing to form a lateral shoulder that supports the outer edge portion of an annular plate 9, formed with a central circular opening, through which 70 the top portion of the containing-vessel projects, so that the inner edge 10 of the plate rests upon the inclined or conical breast 3, and to which said inner edge is soldered or otherwise firmly attached. The annular plate inclines downwardly from its point of attachment to the breast 3 to the shoulder formed by the annular ring or band 8 in such manner that water resulting from melting ice in the ice-chamber 12 will flow outward toward the envelope 80 and through orifices 13 in the plate, so as to percolate down through the antiseptic packing. The outer edge of the annular plate is turned upwardly to form a vertical flange 14, which preferably extends entirely around 85 said plate, and this flange engages a movable retaining-clamp, which, as shown in Fig. 1, is composed of a ring or band 15, secured to the inner side of the envelope directly above the band 8 in such manner that the flange 14 is 90 between the ring 15 and the envelope, while the lower edge of said retaining-ring 15 holds and clamps the annular plate 9 firmly against the top edge of the band 8. By this means the containing-vessel is held in a stationary 95 position in relation to the envelope, and if the latter be overturned or severely handled the containing-vessel will not be displaced. The bottom of the envelope is provided with escape-openings—one or more—closed by stop- 100

pers or plugs 16 for discharging the ice-water as occasion requires.

In the construction above set forth the containing-vessel is not intended to be removed and replaced at will, although such is possible by detaching the retaining and clamping ring or band 15, provided, of course, the internal caliber of the envelope is as great from the band 8 to the top edge of the envelope as the diameter of the annular plate. We have, however, shown the envelope as we prefer to construct it when the container is not adapted for removal. It is sometimes desirable to provide for removing and replacing the containing-vessel without entirely detaching the clamping device that secures the annular inclined plate on the supporting ring or band 8 we provide the construction shown in Fig. 2, where the outer edge of the annular plate 9 is wired, as at 17, and rests on the ring or band 8, while above the latter are pivoted by pins 18 the retaining clamp-plates 19, each having at its lower edge a flange or shoulder 20 to bear against the wired edge 17 and clamp and hold it firmly against the supporting ring or band 8. In this construction we prefer to construct the annular plate in sections, each section being segmental, to permit the plate being conveniently removed and replaced. The inner edge 10 of the plate, instead of being rigidly secured to the inclined or conical breast 3 of the containing-vessel 2, is detachably connected with said breast by spring clamping arms or fingers 21, secured to bearing-plates 22, that are fixed on the breast 3. By turning the retaining clamp-plates 19 on their pivot-pins 18 to disengage their shouldered or flanged ends 20 from the wired edge 17 the latter can be raised and the annular plate be thereby removed from under the spring-arms or fingers 21, after which the containing-vessel can be lifted out of the envelope. The bearing-plates 22 form shoulders or abutments for the inner edge of the annular plate 9 when the latter is inserted under the spring arms or fingers 21, and thus the containing-vessel can be firmly secured in a fixed position within the envelope while permitting its convenient removal when desired.

In Fig. 3 we show the annular plate 9 inclined downward from the band 8 to the inclined breast 3 of the containing-vessel 2, and at its inner lower edge formed with a flange 28, resting on the breast 3 and abutting the bearing-plates 22.

The construction of the envelope 1, spring clamping-arms 21, clamp-plates 19, and other parts not particularly mentioned, is the same as described with reference to Fig. 2.

The arrangement shown in Fig. 3 is very desirable, in that the annular plate 9 operates more effectually as a brace to retain the containing-vessel in correct position should the envelope be overturned.

Having thus described our invention, what we claim is—

1. A packing-refrigerator consisting of an envelope having a ring or band secured to its inside, a containing-vessel having an inclined breast and tight cover, an inclined annular plate provided with orifices resting at its outer edge on the ring or band and connected at its inner edge with the inclined breast of the containing-vessel, and a retaining-clamp for engaging the outer edge of the said annular plate and clamping it on the ring or band, substantially as described.

2. A packing-refrigerator consisting of an envelope having on its inner side a shoulder, a containing-vessel provided with an inclined breast, an antiseptic packing between the envelope and containing-vessel, an inclined annular plate resting at its outer edge on the said shoulder, connected at its inner edge with the inclined breast of the containing-vessel and provided with orifices for the passage of water to the antiseptic packing, and a clamp engaging the outer edge of said plate and holding it upon the said shoulder on the envelope, substantially as described.

3. A packing-refrigerator consisting of an envelope having a shoulder on its inner side, a containing-vessel having an inclined breast provided with movable arms or fingers, an annular perforated plate engaged at its inner edge by the arms or fingers, and movable retaining-plates clamping the outer edge of the plate upon the shoulder on the envelope, substantially as described.

4. A packing-refrigerator consisting of an envelope having a ring or band secured to its inner side, a containing-vessel having an inclined breast provided with bearing-plates and spring arms or fingers, an annular perforated plate engaged at its inner edge by the bearing-plates and the arms or fingers and resting at its outer edge upon the ring or band on the envelope, and pivoted retaining-plates clamping the outer edge of the plate on said ring or band, substantially as described.

In testimony whereof we have affixed our signatures in presence of two witnesses.

LUTHER L. FRIERSON.
JACOB BARKER.
